SHOE RACK

Fred Stein, Long Beach, N. Y.

Application August 27, 1951, Serial No. 16,452

Term of patent 3½ years

(Cl. D80—10)

To all whom it may concern:

Be it known that I, Fred Stein, a citizen of the United States, residing at Long Beach, in the county of Nassau and State of New York, have invented a new, original, and ornamental Design for a Shoe Rack, of which the following is a specification, reference being had to the accompanying drawing, forming part thereof.

Fig. 1 is a front elevational view of a shoe rack, showing my new design.

Fig. 2 is a top plan view thereof.

Fig. 3 is a side view thereof, as seen from the left of Fig. 1.

I claim:

The ornamental design for a shoe rack, substantially as shown.

FRED STEIN.
